ATTORNEY.

UNITED STATES PATENT OFFICE

KARL J. MISLIN, OF KANSAS CITY, MISSOURI

SHOE-STRING FASTENER

Application filed February 17, 1930. Serial No. 429,027.

- My invention relates to fastening devices and while it may be employed to advantage in a number of different places, in the present instance I have shown it applied to a shoe.
- 5 One object of the invention is the provision of a fastening device which will hold a shoe closely and comfortably upon the foot and will require no readjustment after the shoe has once been closed.
- 10 Another object is to provide a fastening device including an elastic strand which will not have to be unlaced to permit removal of the shoe.

In order that the invention may be fully understood, reference will now be had to the accompanying drawing, in which:

- Fig. 1 is a broken plan view of a shoe equipped with the invention.
- Fig. 2 is an enlarged view of the fastening device with the lace in cross section.

Fig. 3 is an enlarged perspective view of a holding member forming an important feature of the invention.

Fig. 4 is a section on the plane of line 4—4 of Fig. 2.

- Referring in detail to the parts disclosed by the drawing, 2 designates the shoe which may be a low shoe as shown, or a high shoe, and is provided with the customary eyelets 4.
- 30 6 designates the lace which consists preferably of a strand of elastic material of circular cross section and of a diameter which will enable the lace to pass easily through the eyelets 4 when the shoe is being laced up.
- 35 The lower end of the strand 6 is attached to a holding member 8 and after said strand has been laced back and forth through the eyelets 4 its upper end is attached to a holding member 10, which is then slid upon the strand 6
- 40 and against the inner surface of the shoe to a point adjacent to the last eyelet through which the strand was laced.
- After the lace 6 has been properly threaded through the eyelets 4 the holding members 8
- 45 and 10 will lie flat between the flaps 12 and the tongue 14 of the shoe and cause no discomfort to the wearer. The holding members 8 and 10 are alike and each has a body 16 consisting of leather, fiber or other suitable material. The body 16 has two apertures

18 spaced apart and communicating with slots 20, each of which latter extends out to the adjacent end of said body, as best shown by Fig. 3. While either of the holding devices 8—10 may be slid upon the lace 6, the latter is of such diameter as to fit snugly within the apertures 18 where it is held from accidental slippage by the inner ends of the inwardly converging sides 22 of the slots 20, and spurs 24 which project from the body 16 into the apertures 18 and compress those portions of the lace 6 which lie within said apertures as shown by Fig. 4.

After the shoe has been laced as stated, it will not have to be unlaced to remove it from, or replace it upon the foot owing to the fact that the lace 6 will stretch sufficiently to permit such removal or replacement without disturbing the holding members 8 and 10.

While I have shown one embodiment of the invention it is to be understood that slight changes may be made, such for instance as substituting a flat disk for the lowermost holding member 8 and permanently attaching the lower end of the lace to said disk. I also reserve all rights to such other changes as properly fall within the spirit and scope of the invention as claimed.

Having thus described my invention, what I claim and desire to secure by Letters Patent, is:

1. A fastening device comprising a lacing, a holding member consisting of a body having apertures through which said lacing is adapted to extend, and spurs projecting from said body into said apertures and engaging the lacing.
2. A holding device of the character described consisting of a body having an aperture therein, and a spur projecting from said body into said aperture.
3. A holding device of the character described consisting of a body having spaced apertures therein, and spurs projecting from said body into said apertures.
4. A holding device of the character described consisting of a body having an aperture therein and a slot with sides converging from the margin of the body to said aperture,

and a spur projecting from the body into said aperture.

5. A holding device of the character described consisting of a body having spaced apertures therein and slots with sides converging from the margin of the body to said apertures, and spurs projecting from the body into said apertures.

In testimony whereof I affix my signature.

KARL J. MISLIN.
